George C. Heinrichs

UNITED STATES PATENT OFFICE.

PAUL GEPAK, OF WARREN, OHIO, ASSIGNOR OF ONE-HALF TO JOSEF SAWA, OF WARREN, OHIO.

COMPASSES.

1,396,417.

Specification of Letters Patent.

Patented Nov. 8, 1921.

Application filed March 24, 1921. Serial No. 455,113.

To all whom it may concern:

Be it known that I, PAUL GEPAK, a citizen of Poland, residing at Warren, county of Trumbull and State of Ohio, have invented certain new and useful Improvements in Compasses, of which the following is a specification.

The present invention relates to improvements in compasses, particularly instruments to be used in topographical work or map work. This compass is furthermore especially well adapted for taking measurements on raised works of art for the use of sculptors or the like.

It is the principal object of the invention to provide a compass of this character which is provided with two movable and one central stationary leg, the points of which are adjustable in longitudinal direction.

A further object of the invention is the provision of a compass of this type which can be conveniently operated by means of an adjusting gear.

With these and other objects in view which will become more fully apparent as the description proceeds the compass is illustrated in the accompanying drawing forming a material part of this disclosure, and in which—

Figure 1 is a front elevational view of an instrument constructed according to the present invention.

Fig. 2 is a top plan view of the same, and

Fig. 3 is a fragmentary end of side view of the central leg or member.

Between the movable legs or members 10 and 11 of the compass which are united at their upper ends in the well known manner, a third substantially vertical and stationary member 12 is provided carrying intermediary its length, a transverse pin 13 provided with an operating grip or handle 14 at its rear, and a head 15 at its front end extending through the member 12.

The pin 13 carries in rear of member 12 and between the same and the handle 14, a gear 16 in mesh with the teeth of two superimposed segments 17 and 18, the upper of which is integral with the member 11, while the lower, 18, is integral with the segment 10, and both segments extend with their free ends in opposite directions beyond the members 10 and 11.

The lower end of the member 12 carries

a socket 19 in which a steel needle or the like 20 is adjustably held by a set screw 21.

The lower ends of the legs or members 10 and 11 are hollowed to form sockets for the pins 22 and 23 adapted to be secured therein.

Near their lower ends the pins 22 and 23 carry longitudinally split sleeves 24 and 25 adapted to be held in their adjusted positions to the work piece by means of clamp screws 26 and 27 respectively.

The instrument operates as follows—

If for instance a sculptor desires to take measurements on a statue or the like, he adjusts the length of the central leg by means of the screw 21 to an elevated point of the statue and can then take the desired measurements by adjusting the split sleeves 24 and 25 by means of the screws 26 and 27 to fit the depressions or crevices of the statue or the like.

Having thus described my invention, what I claim is—

1. An instrument of the class described comprising two movable members, adjustable foot parts at the lower ends of said members, and a stationary member between said movable members, means for simultaneously operating the movable members to be set in any desired angle to said stationary member, said stationary member being provided with a socket, and a needle in said socket adapted to be vertically adjusted and locked in its adjusted position.

2. An instrument of the character described comprising a pair of movable members and a stationary member united at their upper ends, a pair of toothed segments on said movable members, a means on said stationary member engaging said segments for simultaneously operating said movable members to take up any desired angle to the stationary member, and adjustable means on each of said movable members to allow an adjustment of said movable members to fit depressions or crevices of a work piece.

3. An instrument of the character described comprising a pair of movable legs or members, and a central stationary member, all three united at their ends, a pair of toothed segments, one integral with each of the movable members and projecting with their free oppositely directed members over said movable members, a pin transversely

held in said stationary member, a grip on said pin, a gear on said pin between said grip and the stationary member in engagement with both of said toothed segments, 5 a socket on the stationary member, a needle in said socket and a set screw for holding said needle in its adjusted position, needles at the lower ends of said movable members,

split sockets having shouldered feet on said last named needles and clamp screws for 10 clamping said split sockets to said needles for adjusting the sockets with respect to the work piece.

In testimony whereof I have affixed my signature.

PAUL GEPACK.
